INVENTOR

Alfred A. Herbermann
By Conradine C. Billings his ATTORNEY

UNITED STATES PATENT OFFICE.

ALFRED A. HERBERMANN, OF NEW YORK, N. Y.

CRATE FOR EGGS OR THE LIKE.

1,412,742.

Specification of Letters Patent. Patented Apr. 11, 1922.

Application filed November 27, 1920. Serial No. 426,759.

To all whom it may concern:

Be it known that I, ALFRED A. HERBERMANN, a citizen of the United States, and a resident of the borough of Manhattan, city, 5 county, and State of New York, have invented certain new and useful Improvements in a Crate for Eggs or the like, of which the following is a specification.

This invention relates to receptacles, and 10 with regard to its more specific features, to the fillers of the honeycomb type for egg crates or the like.

One of the objects of the invention is to provide a filler of simple and inexpensive 15 construction, which shall effectively protect the brittle contents against destruction from rough handling of the container.

Another object is to provide a filler of 20 the type set forth, which shall preferably be collapsible, shall be easy to assemble, light in construction, and dependable in use.

Another object is to provide a filler with 25 means attached to the same for providing a bottom or layer constituting the flat between the fillers as they are assembled in a crate or shipping receptacle, thus providing a rigid integral structure.

Other objects will be in part obvious and 30 in part pointed out hereafter.

The invention accordingly consists in the 35 features of construction, combination of elements, and arrangement of parts which will be exemplified in the construction herein-after set forth, and the scope of the invention will be indicated in the following claims.

The invention will be understood from the 40 description taken in connection with the drawings, which show one embodiment of the invention in which the same reference characters refer to the same parts in the different views. In the drawings—

Fig. 1 is a transverse section through a 45 crate or shipping receptacle showing a top view of my filler in position.

Fig. 2 is a perspective view of my filler.

Fig. 3 is a side view of one of the strips of which the filler is made.

Figs. 4 and 5 show the respective ends or 50 sides of my filler.

As conducive to a clear understanding of the invention, attention is called to the fact that this invention is concerned principally with the well known type of crate or shipping receptacle comprising a receptacle of

veneer wood or other suitable material, in which is placed a plurality of superposed fillers of the honeycomb type, said fillers being separated or divided from each other by flaps or strips that are attached to or carried by the elements of the filler itself. The filler itself comprises two sets of strips intersecting each other at right angles and interlocked by integral tongue and slot conformations, or otherwise interlocked, to render the filler construction collapsible when not in use, and when in use to provide a combined, yet substantially integral filler and flat, the flat portion affording a strengthening element, so that the filler and flat will 70 be rigid, and one will not move with respect to the other, as is the case when a filler and flat are separable from each other.

In the accompanying drawings the filler is shown as composed of seven strips disposed at right angles to eight other strips. Two of the latter strips are assembled adjacent to each other, and some of the latter strips have flaps or extended portions which can be bent to form the bottom of the filler, 80 as clearly shown in Fig. 2, thus forming a combined filler and flat.

In Fig. 3 one of the strips 1 is shown as having seven tongue and slot conformations, there being a uniform interval 5 between successive conformations. The slots 2 extend substantially half way across the main body of the strip 1. Integral tongues 3 extend across the slots 2. The lower edge of the main body of the strip is provided with a series of holes 4 in line with the slots 2. The strip 1 is extended so as to provide a flap 6 connected along the lower edge of the strip 1. As seen in Fig. 2, the flap 6 is wide enough to extend substantially to the edge of the filler. Another strip 1' with a flap 6', as shown in Fig. 2, is provided, as well as two strips 7 having along their lower edges flaps 8 wide enough to extend from the center of the filler to the respective edges thereof. The flaps 8 are preferably weakened along the lines 9 so that they will bend more readily along this line between the edge which extends along the lower edge of the strips 7 and the outermost edge of the flaps 8. The purpose of this weakened portion 9 will be further described below.

From the description it will be obvious that the individual strips constituting the filler are duplicates of each other except 110

that some of the strips, as indicated, are extended so as to form a flap or bendable portion to constitute the bottom of the filler. Instead of having the flaps integral 5 with the strips themselves the flaps may be made separate and attached along the lower edges of the proper strips in any convenient manner. In order to more easily accommodate the two adjacent strips 7 along the 10 middle portion of the filler the slots 2 in the cross strips may, of course, be made correspondingly somewhat wider.

These fillers are adapted to be placed inside of a receptacle or container C, which is 15 preferably rigid and capable of resisting rough handling. In packing the receptacle or crate a filler, as shown in Fig. 2, will be placed in the bottom of the receptacle with the flaps 6, 6' and 8 lying flat against the 20 lower edges of the strips, thus forming a bottom for the filler which act as re-enforcements or bracers to prevent the relative movement between the honeycomb portion of the filler and the flat or bottom portions. 25 The spaces between the intersecting strips may then be filled with fragile articles to be shipped and another filler superposed thereon whose flaps will likewise lie flat against the lower side of the second filler, thus constituting a cover for the first filler, 30 and so on until the crate or shipping receptacle is filled.

In unpacking the crate it will be obvious that the fragile articles that have been 35 placed in the spaces provided by the intersecting strips can be more readily and more rapidly and conveniently removed than is possible with the ordinary filler. This result can be obtained because with my 40 improved filler it is unnecessary to remove a filler and then afterwards remove a cover or layer between the two fillers, but by merely slightly lifting up my filler the flaps will assume approximately the positions indicated in Fig. 2, so that the articles in the 45 compartments will gradually slide along the flaps toward the outside of the receptacle and will be gathered in two rows on the opposite sides of the receptacle, from which 50 place they can readily be removed. Due to the bends 9 in the flaps 8 the articles that were placed in all the rows of compartments, except the first and last ones, will be enabled to slide gradually down the outside 55 portions of the flaps 8 which are not so steeply inclined, and therefore the articles will be less apt to be broken, but will nevertheless be carried close to the outer edges of the receptacle.

60 My filler may be collapsed when not in use and shipped in the collapsed position, thereby requiring very little space, and then it may be readily distended when ready to be placed in the receptacle or crating box.

65 For certain purposes it may be desirable

to have the flaps 6, 6' and 8 glued or otherwise firmly attached flat against the lower edges of the strips. In such case, when the filler is removed, the articles in the compartment will be bodily removed together 70 with the filler without sliding out of the bottom thereof, as above described.

It is to be understood that the specific form of interlocking connections indicated in Fig. 3 is for illustrative purposes, as 75 other interlocking connections may be used without departing from the spirit or scope of this invention.

It is also to be understood that the number of compartments shown or indicated in 80 the drawings and above described are merely illustrative, that the filler may be made with any desired number of compartments, and that the number of compartments in vertical rows in Fig. 1 may differ from that in 85 horizontal rows. It is also obvious that my filler may be employed in connection with a cardboard box in which eggs are retailed.

It is also to be understood that my invention is not confined in its application to receptacles for any particular articles, but is especially adaptable for many different sorts of fragile articles that are apt to be broken in transit. The compartments may, of course, be made of different shapes to 95 accommodate the different articles to be shipped by merely varying the spacing of the slots for connecting the interlocking strips.

As many changes could be made in the 100 above construction, and many apparently widely different embodiments of this invention could be made without departing from the scope thereof, it is intended that all matter contained in the above description or 105 shown in the accompanying drawings shall be interpreted as illustrative and not in a limiting sense.

I claim:

1. In a filler for a crate, a plurality of interconnected strips and means attached to each of two intermediate strips and extending in opposite directions substantially to the respective edges of said filler to form a 110 complete bottom therefor.

2. In a filler for a crate, a plurality of interconnected strips and means attached to an intermediate strip and extending past a plurality of said strips and substantially to the edges of said filler to form a portion 115 of the bottom of said filler.

3. In a filler for a crate, a plurality of interconnected strips, means attached to one of said strips to cover a portion of the bottom of said filler, and means attached to 120 another one of said strips, said second-named means overlapping said first-named means and each extending to the edge of the filler.

4. In a filler for a crate, a plurality of interconnected strips, one of said strips be- 125

- ing extended and being capable of being bent to form a part of the bottom of said filler and extending to one end of the filler, and another one of said strips being similarly extended and bent to form another part of said bottom and extending to the opposite end of said filler.
5. In a filler for a crate, a plurality of interconnected strips, one of said strips being extended and being capable of being bent to form a part of the bottom of said filler, and another one of said strips being similarly extended and bent to form another part of said bottom, said extensions being 10 bent in opposite directions.
6. In a filler for a crate, a plurality of interconnected strips, one of said strips being extended and being capable of being bent to form a part of the bottom of said 15 filler and extending to the sides and end of said filler, and another one of said strips being similarly extended and bent, the first mentioned of said extensions overlapping the other which latter also extends to the 20 sides and end of the filler.
7. In a filler for a crate, a plurality of interconnected strips, wide flaps attached 25
- respectively to a lower edge of a selected strip, each of said flaps extending to the respective sides and in opposite directions 30 to the respective ends of the filler.
8. In a filler for a crate, a plurality of interconnected strips, some of said strips having flaps attached thereto of sufficient width and length to form a complete and 35 rigid bottom for said filler, said strips and bottom flaps being substantially immovable with respect to each other.
9. In a filler for a crate, a plurality of interconnected strips extending transversely 40 to each other forming spaces therebetween, means attached to one of said strips to cover a portion of the bottom of said filler, and means attached to another one of said strips, said second named means overlapping 45 said first named means, and each extending to the same end of the filler.

In witness whereof, I have hereunto set my hand at the borough of Manhattan, city, county and State of New York, this 26th 50 day of November, 1920.

ALFRED A. HERBERMANN.

In the presence of—

ISABEL R. FLETCHER.
